VEHICLE RADIO ANTENNA AND BASE

Sidney Ludwig, Cleveland, Ohio, assignor to The Tenna
Mfg. Co., Cleveland, Ohio, a corporation of Ohio

Application February 4, 1957, Serial No. 44,746

Term of patent 7 years

(Cl. D14—6)

Fig. 1 is a side elevation of a vehicle radio antenna and base, showing my new design;

Fig. 2 is a front view;

Fig. 3 is a plan view showing the antenna shaft and body rotated approximately 90° relative to the base portion;

Fig. 4 is a front view taken from Fig. 3.

I claim:

The ornamental design for a vehicle radio antenna and base, as shown.
